UNITED STATES PATENT OFFICE

164,354

PHOTOGRAPHIC UNIT

Robert B. Clark, Washington, D. C., assignor to
Hospital Picture Service Corporation, Cam-
bridge, Mass., a corporation of Massachusetts

Application June 30, 1950, Serial No. 10,889

Term of patent 3½ years

(Cl. D61—1)

To all whom it may concern:

Be it known that I, Robert B. Clark, a citizen of the United States, residing at 5028 Massachusetts Avenue N. W., Washington, D. C., have invented a new, original, and ornamental Design for a Photographic Unit, of which the following is a specification, reference being made to the accompanying drawing, forming a part thereof.

The figure of the drawing is a front perspective view of a photographic unit, showing my new design.

I claim:

The ornamental design for a photographic unit, substantially as shown.

ROBERT B. CLARK.
